UNITED STATES PATENT OFFICE.

PETER J. GEORGENSEN, OF TUSTIN, WISCONSIN.

CARBURETER.

1,120,303.

Specification of Letters Patent

Patented Dec. 8, 1914.

Application filed November 24, 1913. Serial No. 802,734.

To all whom it may concern:

Be it known that I, PETER J. GEORGENSEN, a citizen of the United States, residing at Tustin, in the county of Waushara and State of Wisconsin, have invented a new and Useful Carbureter and Vaporizer, of which the following is a specification.

The present invention relates to improvements in carbureters and vaporizers, one object of the invention, being the provision or production of a single structure embodying both a carbureter and vaporizer or air mixer, the same being provided with auxiliary means for supplying air in proportion to the fuel before the delivery of the proportional carbureted air to a mixing device, said mixing device being so disposed as to be heated by the exhaust from the explosion engine so that the proper vaporization and mixture of the carbureted air will be produced before introduction into the explosion chamber of the engine.

A still further object of the present invention is the combination with the carbureted air mixer as shown in my U. S. Patent No. 1,002,670 dated September 5, 1911, with means for properly producing a proportioned carbureted air, so that such carbureted air will be properly delivered through the mixer after which the same is delivered to the explosion engine, there being provided heating means utilizing the heat from the burnt gases of the explosion engine for heating the mixer, so that the carbureted air will be properly heated before introduction to the cylinder, thus insuring the delivery of a perfect explosive mixture to the explosion engine and eliminating all streaks before such delivery.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a vertical sectional view through the complete carbureter and vaporizer. Fig. 2 is a section taken on the line 2—2 of Fig. 1. Fig. 3 is a section through the main air intake taken at right angles to the position as shown in Fig. 1. Fig. 4 is a rear perspective view of the complete carbureter and vaporizer.

Referring to the drawings, the numeral 1 designates the main air inlet pipe which is provided with the butterfly or throttling valve 2, said pipe leading into the enlarged chamber 3 carrying the valve seat port 4 which is controlled by the spring closed puppet valve 5. This valve is rendered adjustable and is adapted to be opened due to the suction action of the explosion engine (not shown). A chamber 6 is provided and into this leads the chamber 3 so that air may be properly delivered therein and into the annular chamber 7 formed by the depressed wall 8 of the float chamber or casing 9. The inverted dome shaped member 10 is disposed concentrically above the chamber 7 and receives the inrushing carbureted air, insuring the delivery thereof through the channel 11 into the mixing chamber 12, the main principal of which covers the rotating fans and streak eliminating device as set forth in my before mentioned patent.

In order to properly heat the mixer and especially the channel portion 11 before the delivery of the carbureted air to and through the mixer, the exhaust pipe 15 is connected to the jacket 16 while the outlet 17 thereof is connected with the continuation 15' of the exhaust pipe. Thus the burnt charges from the explosion engine may be directed to assist in the vaporization and proper heating of the carbureted air during the mixing and delivery thereof through the mixer 12 to the explosion chamber.

The intake 18 by means of which the liquid fuel is supplied to the float chamber 9 is controlled by the valve 19, the lever 20 being connected thereto and actuated by the float 21. This float 21 is an annular member and is disposed about the tapered sleeve 22 mounted centrally of the float chamber 9 and open both at its bottom and top ends, the upper end outletting into the chamber 7 adjacent the inlet end of the chamber 10, while the lower end is in communication

with the port 28 of the air supplying pipe 30, said pipe being held in position by means of the lock nut 29 threaded upon the downwardly projected threaded stem 27, which 5 is properly supported by the cross bars 23^a within the lower end of the sleeve 22. Carried by the cross bar 23^a is the fuel supplying nozzle 23 controlled by the vertically 10 slideable valve 24. This valve is mounted for sliding movement within the sleeve 25 and has disposed upon its upper threaded end, the adjusting and controlling means 26, which is adapted to be operably connected to an automatic means operated by the 15 explosion engine and here not shown. As is usual a butterfly valve 32 is disposed within the primary or main air supplying pipe 30.

From the foregoing description taken in 20 connection with the drawings, it is evident that there is combined here a single structure embodying both the carbureter and the carbureted air mixer or vaporizer so that the same may be readily connected similarly 25 to the connection for carbureters of the present day, to the lower end of the intake manifold of the explosion engine, and thus combine in a unit the two essential mechanisms for delivering to the explosion chamber of the engine, a properly mixed carbureted air and one by means of which the maximum power is obtained at each explosion. It will also be noted that by means 30 of the air inlets 1 and 1^a, that warm or cold air or a proportionate mixture of the same 35 may be admitted into the chamber 3, by means of the valve 2, and as particularly illustrated in Fig. 3 of the drawings.

What is claimed is:

40 1. A carbureter, including a float controlled fuel chamber having a centrally disposed tube open at both ends, a fuel nozzle disposed centrally within the tube and receiving fuel from the chamber, the upper 45 end of the fuel nozzle being slightly below the upper end of the tube, an air supply conduit communicating with the upper end of the tube thereof, an inverted dome shaped member disposed above and in spaced relation to the upper end of the central tube 50 of the fuel chamber for receiving the explosive mixture, a conduit leading from said dome for connection to the intake manifold of an explosion engine, the air intake pipe 55 being provided with two branches for supplying warm and cold air, and a valve disposed in the said pipe at the junction of the two branches for controlling the supply of either the hot or cold air or a combination 60 of the two to the carbureter.

65 2. A carbureter, including a float controlled fuel chamber having a centrally disposed tube open at both ends, a fuel nozzle disposed centrally within the tube and re-

ceiving fuel from the chamber, the upper 65 end of the fuel nozzle being slightly below the upper end of the tube, an air supply conduit communicating with the upper end of the tube thereof, an inverted dome shaped member disposed above and in spaced relation to the upper end of the central tube 70 of the fuel chamber for receiving the explosive mixture, a conduit leading from said dome for connection to the intake manifold of an explosion engine, the air intake 75 pipe being provided with two branches for supplying warm and cold air, a valve disposed in the said pipe at the junction of the two branches for controlling the supply of either the hot or cold air or a combination 80 of the two to the carbureter, and an auxiliary air supplying conduit in communication with the lower end of the central tube of the fuel chamber.

85 3. A carbureter, including a fuel chamber having a centrally disposed tube open at both ends, a fuel nozzle disposed centrally within the tube and terminating at a point below the upper end thereof, a slidably mounted valve for controlling the outlet of 90 the nozzle, the portion of the chamber above the outlet end of the tube being depressed to form a cup, an air supplying conduit leading from above and in communication with said cup, an inverted cup shaped member of 95 lesser diameter than the depression of the fuel chamber disposed above and in spaced relation from the depressed portion of the fuel chamber, and forming an outlet and directing means for the carbureted air, a 100 conduit leading from the cup shaped member to direct the carbureted air to the manifold of an explosion engine, and a valve controlled conduit in communication with the lower end of the central tube of the fuel 105 chamber for controlling the supply of air thereto.

110 4. A carbureter, including a fuel chamber having a centrally disposed tube open at both ends, a fuel nozzle disposed centrally within the tube and terminating at a point below the upper end thereof, a slidably mounted valve for controlling the outlet of the nozzle, the portion of the chamber above the outlet end of the tube being 115 depressed to form a cup, an air supplying conduit leading from above and in communication with said cup, an inverted cup shaped member of lesser diameter than the depression of the fuel chamber disposed above and in spaced relation from the depressed portion of the fuel chamber and forming an outlet and directing means for 120 the carbureted air, a conduit leading from the inverted cup shaped member to direct 125 the carbureted air to the manifold of an explosion engine, a valve controlled conduit in communication with the lower end

of the central tube of the fuel chamber for controlling the supply of air thereto, the main air intake conduit being provided with two branches for the introduction of hot 5 and cold air, and a valve disposed at the junction of the two branches for controlling the supply of such air to the carbureter.

In testimony that I claim the foregoing as my own, I have hereto affixed my signature in the presence of two witnesses.

PETER J. GEORGENSEN.
